UNITED STATES PATENT OFFICE.

FRANK JENNINGS, OF WINSLOW, INDIANA.

HOLDING CHAIR FOR RAILS.

Application filed October 16, 1923. Serial No. 668,816.

To all whom it may concern:

Be it known that FRANK JENNINGS, a citizen of the United States, residing at Winslow, in the county of Pike and State of Indiana, has invented new and useful Improvements in Holding Chairs for Rails, of which the following is a specification.

It is the purpose of the present invention to provide, in a holding chair for rails particularly in mines, a construction wherein the retaining parts or elements are capable of freedom of movement when it is desired to remove the rails from their holding positions in the chair.

Another purpose is to provide a holding chair for the reception of a track rail, together with a rail section disposed on its side and in engagement with the chair with its ball engaging the side of the web under the ball of the upright rail, together with a wedging key to hold the clamp detachably in place on the track rail and yet permit free adjustment of the rail section without releasing the clamp from its position on the track rail.

A still further purpose is to provide a holding chair wherein a rail section may be inverted so that its ball may engage the base of the upright rail instead of the web, there being means provided on the chair for retaining the inverted rail section in an inverted position, while permitting longitudinal adjustment of the same.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a side view of the holding chair with a rail in an upright position and a holding rail section disposed on its side with its ball engaging the web of the upright rail with the retaining key in place upon the opposite side.

Figure 2 is a plan view.

Figure 3 is a detail perspective view of the retaining wedge.

Figure 4 is a detail view in perspective of the chair.

Figure 5 is a side view showing a modified form of holding chair particularly adapted for the reception of an inverted rail section with the ball engaging the base 60 of the upright rail.

Figure 6 is a plan view of Figure 5.

Figure 7 is a detail view of the chair shown in Figures 5 and 6.

Referring to the drawings, 1 designates 65 a holding chair for the reception of an upright rail 2. The chair has a seat 3 with which the base of the upright rail engages, there being a flange 4 rising from the seat and overlying the base 5 of the upright 70 rail. The chair opposite the flange 4 has a wall 6 which overhangs the seat of the chair. The under surface 7 of this wall is inclined and engaging therewith is a key 8. The under surface 7 of the wall is not only inclined toward the bottom of the seat but it is also inclined or angularly disposed relatively to the base of the upright rail.

The key 8 is tapered throughout its length, 80 therefore has a wedging action with the surface 7. The key 8 also has a shoulder 9 to engage with a portion of the wall 6 to limit the key in its position when engaged with the surface 7. The key has an angular channel or recess 10 of a contour to conform to one side of the base of the upright rail, thereby acting to retain the rail in position and prevent its upward movement. The key also engages the seat of the chair and since the key is tapered, it acts to force the base of the upright rail toward and in engagement with the flange 4, to securely lock the chair clamp to the base of the upright or fixed rail.

An extension rail section 11 is provided and 95 constitutes a guard rail for the upright rail. This rail section is disposed on its side, in fact, so that its ball 12 engages with the web of the upright track rail under the ball. The holding chair has an upstanding flange 13 100 with which the rail section 11 engages to retain the ball of the rail section under the ball of the upright rail and in engagement with its web and its base. A slight space intervenes between the flange 13 and the base 105 of the rail 11 which permits the rail 11 to be slid longitudinally to project the end of the extension rail farther from the fixed rail without releasing the clamp 1 from the fixed rail, the length of the flange 13 being such that when the head 12 of the rail 11 is against the rail 2, the sidewise move-

ment or spreading of the rail 11 is substantially prohibited.

The holding chair is provided with an eye 14 to which a chain 15 is connected, the chain being, in turn, connected to the key so as to prevent loss thereof.

In Figures 5, 6 and 7, the construction of the holding chair is substantially the same as that in Figures 1 to 4, inclusive, with the exception that the rail section 16 is inverted so that its ball 17 may engage with one side of the web of the upright rail 18 adjacent its base. Also in this construction, the upstanding flange 13^a has a lateral part 19 which engages with the web of the inverted rail and acts to retain the ball 17 of the rail 16 in engagement with the base of the upright rail. In this construction, the base of the inverted rail section not only acts as a guard but also acts as means to insure against outward deflection of the upright rail.

The holding chair in addition to constituting the support to hold a rail section on the side of an upright rail as a guard also constitutes means to support a rail section in position on its side or inverted in order to be convenient at all times for the purpose of temporary or permanent extension of a mine track.

Naturally, as the coal is dug away from the wall of a mine, the space between the end of the mine track and the wall increases and at times it is necessary to provide a temporary extension of the track before the extension is made permanent, hence it is necessary to have rail sections close at hand in order to make a temporary or a permanent extension of the track, so that the mine cars can come closer to the wall from which the coal is removed.

With this idea in view, the present invention aims to provide a holding chair which is clamped to the permanent track rails (which are spiked down to the ties). The holding chair is clamped to such upright spiked down track rails by means of the wedge, the wedge engaging on one side of the base of the upright rail and the flange 4 overlying the opposite side. In order that the holding chair may provide a support for a rail section so that it will at all times be close at hand, the chair is provided with an angular extension, the upright wall 13 of which acts to retain the rail section 11 in a position on its side with its ball 12 under the ball of the upright rail and resting upon the base thereof.

It will be noted that there is sufficient space between the base of the rail section 11 and the wall 13 so that the rail section 11 may have free movement so that it may be easily inserted and removed or extended by sliding the same the full length of the upright rail 2. In Figure 5, the rail section

16 is inverted and is loosely supported for free movement between the upright rail and the lateral part 19 of the wall 13^a. When the rail section 16 is so disposed, it may also constitute an abutment for the car wheels. 70 However, the car wheels may ride over the base of the inverted rail section in order that the mine car can come very close to the wall from which the coal is being removed.

As previously stated, the upright rail section 2 is designed to be spiked down and stationary to the ties. The holding chair is applied, in fact, two of them may be used on the upright rail 2, although only one is illustrated. The two chairs are disposed in position on the upright rail a distance approximately equal to the length of the rail section 11 which is to be disposed upon its side. The chair is secured fast to the upright rail 2 by driving the wedge or key 8 between the surface 7 of the overhanging wall 6 and the base of the upright rail, so that the wedge may be clamped upon the upright rail base on one side with the flange 4 on the other side. This holds the chair securely in position.

It is possible to slide or slip the rail section 11 between the web of the upright rail and the wall 13 of the chair. This rail section 11 may have free movement back and forth the length of the upright rail. When the rail section 11 is removed or slipped out of its position its full length, the wedge or key 8 may be removed, permitting detachment of the chair. The rail section 11 can then be turned to an upright position and spiked down. The holding chair may then be applied to the last spiked down rail section, that is, the rail section which has been removed from the position on its side to an upright position. Another rail section is then disposed upon its side or inverted, as in Figures 1 and 5, and slipped loosely in the holding chairs, so that this rail section may at all times be close at hand in order to constitute a part or a section of the track when it is desired to extend the mine track.

In order that a rail section which is disposed upon its side or inverted can have freedom of movement when supported upon its side, the space between the wall 13 and the upright rail is greater in width than the height of the rail section in order that said rail section may have free movement, whereby it can be slipped from the end of the upright rail to full length of the rail section which is disposed upon its side without removing the key.

It is to be borne in mind that the spaces between the ball of the upright rail 18, the part 19 and the web of the inverted rail and the space between the base of the rail section 11 and the part 13 are merely illustrative of the fact that the inverted rail section 16 and the rail section 11 are capable 130

of freedom of movement and not that such rail section should not engage the ball of the upright rail and the parts 13 and 19. In other words, the inverted rail section 16 and the rail section 11 should be inserted in positions in actual practice, so as to engage with the upright rail and the part 13 and yet be capable of freedom of movement in order to permit the inverted rail section 16 or the rail section 11 to be easily inserted manually without using any extra power or exertion.

The invention having been set forth, what is claimed is:

- 15 1. In a rail holding device, a chair provided with a seat, an upright rail disposed with its base engaging the seat, means rising from the seat and overlying one side of the base of the upright rail, said chair 20 having a wall overlying the opposite side of the base of the upright rail, a wedge key engaging between the overlying wall and the base of the upright rail, a rail section constituting a track rail retaining element 25 disposed whereby its ball may engage with the upright track rail, and means for retaining the rail section in position.
2. In a rail holding device, a chair provided with a seat for the reception of the 30 base of an upright track rail and provided with a wall at one side of the seat, means rising from the seat to retain one side of the base of the track rail in position, a locking key wedgedly engaging between the wall 35 of the chair and the opposite side of the base of the track rail to hold the same in position, means connecting the chair and the locking key to prevent the loss of the latter, a rail section constituting an upright track 40 rail retaining element disposed in the chair with its ball engaged with the upright track rail, and means to retain the track section in position.
3. In a rail holding device, a chair provided with a seat for the reception of the 45
- base of an upright track rail and provided with a wall at one side of the seat, means rising from the seat to retain one side of the base of the track rail in position, a locking key wedgedly engaging between the wall 50 of the chair and the opposite side of the base of the track rail to hold the same in position, means connecting the chair and the locking key to prevent the loss of the latter, a rail section constituting an upright track 55 rail retaining element disposed in the chair with its ball engaged with the upright track rail, and means to retain the track section in position.
4. In an extension rail holding device, a chair, means to detachably clamp the chair to a fixed rail, and means on the chair to hold an extension rail in engagement with the fixed rail, and to substantially prevent sidewise movement of the extension rail, the space between the fixed rail and the extension 60 rail holding means of the chair being slightly larger than the dimension of the extension rail held therebetween to permit longitudinal adjustment of the extension rail without releasing the chair from the 65 fixed rail.
5. In an extension rail holding device, a chair, means to releasably clamp the chair to one rail, means on the chair to hold a second rail between the holding means and the first rail, said holding means being spaced from the first rail a sufficient distance to permit longitudinal movement of one rail relative to the other but being near enough to the first rail to prevent removal of the second rail from the chair except by said longitudinal movement.

In testimony whereof he affixes his signature.

FRANK JENNINGS.
